[57] CLAIM

The ornamental design for a battery housing, as shown and described.

DESCRIPTION

FIG. 1 is a right, front, bottom view of first embodiment of a battery housing, showing our new design; FIG. 2 is a front elevation view thereof; FIG. 3 is a left side elevation view thereof; FIG. 4 is a bottom elevation view thereof; FIG. 5 is a top elevation view thereof; FIG. 6 is a rear elevation view thereof; and, FIG. 7 is a right side elevation view thereof; FIG. 8 is a right, front, bottom view of second embodiment of a battery housing, showing our new design; FIG. 9 is a front elevation view thereof; FIG. 10 is a left side elevation view thereof; FIG. 11 is a bottom elevation view thereof; FIG. 12 is a top elevation view thereof; FIG. 13 is a rear elevation view thereof; and, FIG. 14 is a right side elevation view thereof.

The broken line matter in FIGS. 1-7 is included for the purpose of illustrating environmental structure only and forms no part of the first embodiment.
